JOHN HOWARD JOHNSTON, OF PARIS, FRANCE.

CARBURETER FOR HYDROCARBON-ENGINES.

No. 802,216.

Specification of Letters Patent.

Patented Oct. 17, 1905.

Application filed September 14, 1903. Serial No. 173,102.

To all whom it may concern:

Be it known that I, JOHN HOWARD JOHNSTON, engineer, a citizen of the United States, residing at 145 Rue de la Pompe, Paris, France, 5 have invented certain new and useful Improvements in Carbureters for Hydrocarbon-Engines, of which the following is a specification.

This invention relates to improvements in 10 carbureters for hydrocarbon-engines or motors, and has for its object to provide a carbureter in which the admission of the air for the formation of the explosive mixture shall be automatically regulated according to the extent of aspiration of the engine or motor, 15 and consequently according to the speed of the latter, in such a manner that the richness of the explosive mixture will always remain at the most suitable point for the proper working of the motor. For that purpose the admission of the hydrocarbon, as 20 well as that of the air to be carbureted, is regulated by a novel means consisting in a mass of mercury or other suitable liquid 25 which is placed in vessels communicating with each other, in one of which the aspiration of the motor acts in such a manner that the liquid in it is raised to a less or greater height, according as the aspiration is weaker or 30 stronger. The oscillations of the liquid which are thus produced act on the passage of the hydrocarbon or of the air so as to obstruct the said passage when the aspiration of the motor decreases and to facilitate the same when the 35 aspiration increases, and this result can be obtained as well by the mass of liquid itself, which uncovers more or less the orifices of the duct, which are suitably arranged for the hydrocarbon or for the air, as by means 40 of obturating devices, such as valves and the like, which are located in front of the openings for the hydrocarbon or the air and operated by a floating mass on the oscillating liquid. This regulating means is most ad- 45 vantageous, in that it offers, even when the dimensions are small, a very great sensibility and cannot get out of order on account of the absence of springs, diaphragms, or other devices giving rise to friction. How- 50 ever, to make the regulation precise and efficient it is necessary to prevent the mercury from oscillating suddenly or from becoming tumultuous by agitation or from separating into several parts under the action of the aspirations of the motor or of shocks—for instance, when the carbureter is mounted on a

motor-car. For that purpose I use the resistance which molecular attraction opposes to the rapid displacement of liquids when confined in tubes or vases in arranging in one or 60 several of the vases communicating with each other and above the mercury floats which are of slightly smaller diameter than that of the vases and a liquid which wets the walls of the vases. 65

The invention consists also in the combination of the aforesaid devices for regulating the hydrocarbon and the air with a device for regulating the explosive mixture and which comprises two slide-valves sliding one against 70 the other, one of which is operated by hand and the other which is operated by the centrifugal governor of the engine or motor in such a manner that the amount of explosive mixture aspirated by the motor can be modified by one of the slide-valves at the will of the driver, while it remains constantly regulated by the other slide-valve in accordance with the speed of the motor, the said amount decreasing when the speed increases, and vice 75 versa. 80

The accompanying drawings show, by way of example, several forms of my improved carbureter.

Figure 1 represents a vertical section of 85 carbureter in which are incorporated the features of my invention. Fig. 2 is a vertical section of the same on the line A B of Fig. 1. Fig. 3 is a horizontal section on the line C D of Fig. 1. Fig. 4 shows in vertical section a 90 modified form of the arrangement for regulating the hydrocarbon. Figs. 5 and 6 are vertical sections of other modified forms of the invention. 95

The apparatus shown in Figs. 1 to 3 comprises a suction-box 1, carrying a feed-pipe 2 for the hot air, a pipe 3, connected to the suction-valve of the motor, and a vessel or vase 4, the top of which is connected by a duct 5 with a receptacle (not shown) containing the hydrocarbon and in which the hydrocarbon remains constantly at the same level. The box or casting 1 is also connected to a chest 6, provided with slide-valves for regulating the passage of the pure air and of the explosive mixture. 100 In the vessel 4 is immersed a spray-pipe 7, the upper end of which opens into the center of a tube 8 in the form of a funnel located in the casing 1. The vessel 4 contains a certain quantity of mercury 9, which is able to rise 105 in the spray-pipe 7 in passing through its lower end. The side of the pipe 7 is pierced 110

by holes 10 11 12 for the passage of the hydrocarbon. The quantity of mercury is such that when the motor is at rest the upper hole 10, which is very small, is the only one 5 uncovered by the mercury. When the motor is started and so long as the speed of the same does not go beyond a certain point, the hydrocarbon can pass exclusively through the hole 10 in the spray tube or pipe and penetrate into the tube 8, to become vaporized in 10 the hot air sucked in at 2, in passing afterward to the motor through the pipe 3. Under the effect of the aspiration of the motor in the tube 8 on the one hand and the constant 15 pressure (atmospheric pressure increased by a constant column of hydrocarbon) acting in the vessel 4 on the other hand the mercury rises in the spray-pipe 7 and falls in the vessel 4, when the following phenomenon occurs: A little before the level of the 20 mercury around the spray-pipe has gone down as far as the hole 11, Fig. 1, the hydrocarbon descends between the mercury and the outer wall of the said pipe, passes through 25 the hole 11, and rises in the spray-pipe between the inner wall of the latter and the mercury. There is thus produced an inverted siphoning of the hydrocarbon between the walls of the spray-pipe and the mercury on 30 account of the aspiration in the latter, so that the passage of the hydrocarbon is increased in spite of the rise of the mercury in the pipe 7. If the aspiration of the motor becomes stronger, the mercury uncovers the hole 11 at 35 the outside and the hydrocarbon passes more rapidly through the said hole to rise up again between the inner wall of the spray-pipe and the mercury contained in the latter. For a still-stronger aspiration the hydrocarbon can 40 also pass through the hole 12 in the same manner. There is thus obtained for the hydrocarbon a passage which is all the more easy as the aspiration is stronger, and the number and the spacing of the holes, such as 45 those 10 11 12, can be so regulated by experiments that the richness of the mixture formed in the tube 8 will be as constant as possible or will vary according to a suitable law. In the chest 6 there are pierced for the 50 admission of a supplementary quantity of air openings 13, which are more or less obstructed by cylindrical drawer or slide-valve 14, the rod 15 of which is supported by a weight 16, floating on a mercury-bath 17. The said mercury is contained in the vessels, communicating with each other, 18 and 19 19^a 19^b, the three latter being located symmetrically around the former and being each provided with an outlet 20, opening into the open air. 55 Under the influence of the aspiration produced by the motor in the chest 6, and consequently in the vessel 18, the mercury rises in the latter, so that for different degrees of depression the drawer or valve 14 uncovers more or less the openings 13 and admits into the

chest 6 a supplementary quantity of air, which becomes mixed with the carbureted air issuing from the tube 8 when admitted into the tube 3. By the concentric arrangement of the vessels 19 19^a 19^b I nullify the disturbing influence of the leaning movements of the carburetor, which would bring about a variation in the levels in the vessels independently of the depression caused by the motor. To regulate the section of the passage for the explosive mixture, I arrange in the chest 6 two concentric tubular drawers or slide-valves 21 and 22 opposite the tube 8, the two drawers or valves being capable of being brought nearer the latter, so as to more or less narrow the passage 75 for the mixture of carbureted air and of air which is drawn in through the pipe 13. The drawer or valve 21 is provided with an operating-rod 23, by which it is connected to a regulating device in the form of a centrifugal 80 governor (not shown) in order to render narrower and narrower the passage for the mixture as the speed of the motor increases. The drawer or valve 22 is connected by a rod 23^a (see Fig. 2) to any suitable controlling device 85 (not shown) operated by hand. This system of regulation by means of independent drawers or valves is very compact and very simple in construction. In order to prevent the jolts received by the carburetor from causing the 90 mercury to splash out of the vessels, I locate in the spray-pipe 7, as well as in the vessel 19, iron balls 24 of a slightly smaller diameter than the walls surrounding the same. It is also advantageous to give to the weight 16 a 95 spherical or segmental shape of a diameter slightly smaller than that of the vessel 18. Besides it is important to place above the mercury in the vessel 18 or in the vessels 19 or in all these vessels a layer of liquid 100 25— 105 water, for instance, or glycerin or the like, which on account of the molecular actions opposes the sudden displacements of the mercury. 110 Fig. 4 shows a modified form of device for regulating the passage of the hydrocarbon and in which the hydrocarbon is fed through a tube 5^a into a vessel 4^a, on the top of which is mounted the spray-pipe 7^a. The said tube 5^a dips into the mercury 9^a, contained in the 115 vessel 4^a, and is provided in one side with a small hole 10^a above the mercury and with several holes, such as those 11^a 12^a, located below the level of the mercury when at rest. When the aspiration of the motor acts at the 120 orifice of the spray-pipe, the hydrocarbon passes in small quantities through the hole 10^a and the mercury rises in the vessel 4^a and falls in the tube 5^a. When the aspiration is sufficiently strong, one or more of the holes 11^a 12^a become uncovered within the tube 5^a, 125 and the hydrocarbon drawn through the said holes rises between the outer wall of the tube and the mercury surrounding the same in a manner similar to that described in reference 130

to Fig. 1. The arrangement shown in Fig. 4 permits of very easily giving to the tube 5^a and to the vessel 4^a diameters which are very different, so that the mercury falls in the 5 tube 5^a to a much greater extent than that in which it rises in the vessel 4^a, the sensibility of the regulation thus becoming much greater. By locating the tube 5^a in the center of the vessel 4^a I nullify the influence of the various 10 leanings of the carbureter on the level of the mercury. 24^a designates iron balls arranged on the mercury around the tube 5^a to prevent it splashing under the action of jolts.

In the foregoing description it was assumed 15 that the liquid subjected to the action of aspiration in the vessels communicating with each other was mercury; but I may use any other suitable liquid—water, for instance—provided I increase the depth of the vessels in taking 20 into account the difference of the densities. I may use liquids less dense than mercury, and especially when the carbureter is a fixture and when the apparatus may be of greater size.

25 The passage of the hydrocarbon into the spray-pipe 7 is regulated by the mercury itself in the example shown; but I may without departing from the invention regulate the said passage by means of any obdurate device—30 a conical needle, for instance—connected to a float located in one of the vessels communicating with each other, as shown in Fig. 5. In this figure 19^c and 19^d represent the two communicating vessels, 26 the hydrocarbon-valve, and 16^b the float in the vessel 19^c and connected to said valve. The aspiration of the motor acts in 19^d, while the mercury in 19^c is subjected to atmospheric pressure increased by the height of hydrocarbon contained in the hydrocarbon-reservoir. (Not 40 shown.)

Instead of regulating the passage of the explosive mixture by means of a drawer or slide-valve 21, controlled by the centrifugal governor, I may obtain this result by means of a 45 drawer or a valve or the like, operated by a mass of liquid oscillating in vessels communicating with each other, in one of which the aspiration of the motor acts, while atmospheric pressure acts in the other, as shown in Fig. 6. In said figure 19^e and 19^f represent the two communicating vessels; 27, a gas-valve; 16^b, the float in the vessel 19^e and connected with the valve, and 17^a the mercury in 55 the said vessels. In the vessel 19^e the aspiration of the motor acts while vessel 19^f is subjected to atmospheric pressure.

I claim—

1. In a carbureter for explosion-motors, 60 means for regulating each of the fluids of the combustible mixture, operated directly by the suction of the motor, each means comprising vessels communicating with each other and containing a mass of mercury, a communication between one of the said vessels and the

suction-tube, and a passage for one of the said fluids regulated by the displacements of the mercury which oscillates in the vessel in concordance with the greater or less suction of the motor. 70

2. In a carbureter for explosion-motors, a device for regulating the fuel, comprising a vessel containing a mass of mercury, a tubular vessel, the lower end of which is open and immersed in the mercury, and in the walls of which are orifices beneath the level of the mercury, a fuel-inlet to the first vessel above the level of the mercury, and a suction-pipe connected to the top of the tubular vessel. 75

3. In a carbureter for explosion-motors, a device for regulating the passage of the air comprising two vessels communicating with each other, a liquid in the said vessels, a communication between the second vessel and the outer air, a float located in one of the vessels, 85 an orifice for the admission of the air, and a drawer or slide-valve located in front of the said orifice and connected to the said float.

4. In a carbureter for explosion-motors, a device for regulating the passage of the air 90 comprising vessels communicating with each other, a communication between one of the said vessels and the suction of the motor, mercury in the said vessels, an orifice for the passage of the air, means for regulating the 95 said orifice and which are operated by the said mercury, a float on the mercury in one of the vessels and having a diameter somewhat smaller than that of the vessel, and a liquid 100 of less density than the mercury in the said vessel.

5. In a carbureter for explosion-motors, a device for regulating the passage of the air comprising vessels communicating with each other, a liquid in the said vessels, a communication between one of the vessels and the suction of the motor, an orifice for the passage 105 of the air, and means for regulating the said orifice and which are operated by the said liquid, the last-mentioned vessel being located 110 in the center of the others in order to nullify the influence of the various leanings of the carbureter on the level of the liquid in the said central vessel.

6. A carbureter for explosion-motors, comprising a device for regulating the hydrocarbon and a device for regulating the air, the said devices being operated separately by the suction of the motor, vessels communicating with each other, and masses of liquid in the 115 said vessels to operate the said regulating devices, and a device for regulating the mixture of hydrocarbon and of air, comprising two drawers or slide-valves sliding the one against the other and independently the one of the other. 120

7. A carbureter for explosion-motors, comprising a suction-pipe connected with the motor, a funnel in communication at its base with the said suction-pipe, a spraying-nozzle 130

extending into the shank of the funnel, a hot-air-supply pipe opening onto the apex end of the funnel, an automatic liquid-fuel supply for the said nozzle, an air-inlet for the said suction-pipe, opposite the base end of the funnel, and automatic means for regulating the said air-inlet to admit more or less air, as set forth.

8. A carbureter for explosion-motors, comprising a suction-pipe connected with the motor, a funnel in communication at its base end with the said suction-pipe, a spraying-nozzle extending into the shank of the funnel, a hot-air-supply pipe opening onto the apex end of the funnel, an automatic liquid-fuel supply for the said nozzle, comprising a vessel for containing mercury and a tube extending into the vessel and immersed with its lower open end in the said mercury, the tube having per-

forations in its side, and means for supplying 20 the liquid to the said vessel, as set forth.

9. A carbureter for explosion-motors, provided with a spraying-nozzle for the liquid fuel, a vessel for containing mercury, connected with a liquid-fuel supply, and a tube 25 extending into the vessel and immersed with its lower open end in the mercury, the said tube having in its side perforations located one above the other, to establish communication between the vessel and the tube, as set 30 forth.

In testimony that I claim the foregoing as my invention I have signed my name in presence of two subscribing witnesses.

JOHN HOWARD JOHNSTON.
